UNITED STATES PATENT OFFICE.

EDMOND JOSEPH ROULLIÉ AND LÉONCE ALEXIS SINGIER, OF PARIS,
FRANCE.

CAR-COUPING.

SPECIFICATION forming part of Letters Patent No. 381,033, dated April 10, 1888.

Application filed August 8, 1887. Serial No. 246,450. (No model.) Patented in France November 26, 1886, No. 179,900.

To all whom it may concern:

Be it known that we, EDMOND JOSEPH ROULLIÉ and LÉONCE ALEXIS SINGIER, both citizens of the Republic of France, and residing in Paris, France, have invented certain Improvements in Car-Couplings, (for which we have obtained French Letters Patent No. 179,900, dated November 26, 1886,) of which the following is a specification.

Our invention consists of an improved automatic car-coupling, designed with a view of insuring the coupling of the cars even on curves of the shortest possible radius, and to prevent accidental uncoupling.

In the accompanying drawings, Figure 1 is a side view of the coupling, with parts of the car-frames in sections. Fig. 2 is a plan view, partly in section. Fig. 2^A is a similar view showing the parts about to be coupled. Fig. 3 is a sectional view through the coupling-jaws on one of the cars. Fig. 4 is a longitudinal section drawn to a smaller scale. Fig. 5 is a corresponding plan view, showing portions of the car-frames, as well as the coupling mechanism; and Fig. 6 is a corresponding end view of one of the cars.

Our improved coupling is of that class in which an eye or loop on one car acts in combination with a pair of spring-jaws, M M', on the other car.

We prefer in all cases to provide each end of each car with both devices—that is, the loop and the jaws so arranged on each car that the loop on one may engage with the jaws on the other, as illustrated in the plan view, Fig. 5.

In the present instance we have shown the eye or loop a b c as in the form of a triangle and forming part of a rigid draw-bar, A, carried by the car-frame, and the eye or loop is shown as in a vertical plane. The side b c of the eye or loop is shaped like a knife-edge, as shown in Fig. 2, and the faces of the jaws M M' are beveled or inclined, as shown at n n', in Figs. 2 and 2^A, so that when the eye or loop approaches the closed jaws on the approach of two cars the eye or loop will itself enter between and open the jaws, which are normally kept closed by a suitable spring or springs, R, acting on their lever-arms m at the rear.

The two jaws M M' are pivoted together by a central pin or pivot, O, Fig. 3, and they are so connected to the yoke F on the draw-bar of the car that the more pulling strain is put on them the more the jaws M M' will tend to close. For this purpose the lever-arms m of the pivoted jaws are connected by pairs of links l l' to the arms of the yoke F. Pivot-pins e pass through the arms and the outer ends of the links, while pins t t' connect the inner ends of the links together and to the arms of the yokes, as shown in Fig. 3. These links we have shown as being both above and below the pivoted jaws M M', and they are always set at an angle to each other, so as to form in effect a toggle-joint, to the center of which the yoke F is connected, as shown in Fig. 2, so that the more pulling strain is put upon the coupling the more difficult will it be for the jaws to open. Thus there is no danger of the cars becoming uncoupled under pulling strains.

Slotted bars S S' connect the two pins e e. One bar, S', may be acted on by the short-arm p, or an upright pivoted lever, P, to be operated from the end platform of the car, as shown in Figs. 1, 3, 4, 5, and 6, or the bar S may form part of the lever p, Figs. 2 and 2^A, and be extended out toward the side of the car for uncoupling from that point by bars T, connected together within the car-frame by a cross-bar, T'. As shown in Figs. 4 and 5, this bar T' is composed in the present instance of two plates having midway between them a swiveled nut, p', through which passes the threaded portion of a longitudinal rod, N. The outer end of this rod is acted on by a spring, R', which constitutes the draw-spring.

The screwed rod N is provided with a worm-wheel, V, rigidly fixed on the rod N and gearing with an endless screw, F', keyed upon a transverse shaft, Z, which is supported in suitable bearings, and whose extremities at each side of the car are provided with hand-wheels Y. By turning these wheels in a given direction the screwed rod N is screwed into the swivel-nut, Fig. 4, and the coupling is thereby tightened. This rod N receives all the strain of the traction independently of the tightening action—that is to say, it is always free to move longitudinally. It is also to be observed that the long arm of the lever P

- stands in a vertical position and terminates in a handle, and that it works over a toothed sector or guide, D, which retains it in the required positions for coupling or uncoupling.
- 5 The handle, as indicated in Figs. 4 and 6, is placed conveniently within reach of the brakeman, who is stationed on the end platform of the car and is not required to go between the cars to couple or uncouple them.
- 10 The operation of coupling with the aid of this apparatus is most simple. When two vehicles are brought together, the draw-bars present the knife-edges at *b c* on the loops or eyes *a b c* between the jaws M and M', which have 15 corresponding inclines *n n'*, and are thereby opened to admit the loop, and then are closed automatically by the action of the spring R, so as to confine it. When thus locked together, the bars remain free in the plane perpendicular to the lever without any danger of breakage. Moreover, the length of the jaws is such that the loops cannot knock against the back even when the buffers are screwed or pushed up as far as they will go. To uncouple, 25 it suffices to push over the lever P on each car, so as to cause the bars S S' to move backward and compel the jaws to turn on their axis or pin O, Fig. 7, and thus free the eyes when it is desired to separate the cars.
- 30 In the arrangement hereinbefore described the jaws M and M' are situated in a horizontal plane; but they may be arranged to work in a vertical plane while the eyes or loops are placed horizontally. In all other respects the 35 apparatus need undergo no modification; but it is advisable to place the draw-bar on a horizontal axis at *x*, so that the said bar may assume any required inclination or angle in accordance with possible unequal heights or 40 inequalities in the level of the vehicles to be coupled.

The bar can be retained in the horizontal position or inclined at any desired angle by means of one or more ratchet-wheels fixed on the axis or pin of the joint, and retained in any 45 desired position by means of spring-paws attached to a fixed support.

The operating-lever P is so arranged as to admit of being worked from the end platform of the car or from either side of the car. 50

We claim as our invention—

1. An automatic car-coupling comprising an eye or loop on one car, in combination with a pair of spring-jaws on the other car, a supporting-yoke for these jaws, and toggle-joint links 55 connecting the lever-arms of the jaws with the supporting yoke, substantially as and for the purpose set forth.

2. An automatic car-coupling comprising an eye or loop on one car, in combination with a 60 pair of spring-jaws on the other car, a supporting-yoke for these jaws, toggle-joint links connecting the lever-arms of the jaws with the supporting yoke, and an operating-lever also connected to the said lever-arms, substantially 65 as described.

3. An automatic car-coupling comprising a bar having an eye or loop on one car, in combination with a pair of jaws on the other car, a draw spring and rod for each, and devices 70 for regulating the tension, substantially as described.

In testimony whereof we have signed our names to this specification in the presence of two subscribing witnesses.

EDMOND JOSEPH ROULLIÉ.
LÉONCE ALEXIS SINGIER.
